PIANO CASE

William Millington, Grand Rapids, Mich., and Wilbur M. Day, Kenwood, Ohio, assignors to
The Baldwin Company, Cincinnati, Ohio, a corporation of Ohio

Application June 15, 1951, Serial No. 15,548

Term of patent 14 years

(Cl. D56—9)

To all whom it may concern:

Be it known that we, William Millington and Wilbur M. Day, citizens of the United States of America, residing at Grand Rapids, in the county of Kent and State of Michigan, and at Kenwood, in the county of Hamilton and State of Ohio, respectively, have invented a new, original, and ornamental Design for a Piano Case, of which the following is a specification, reference being had to the accompanying drawing, forming a part hereof.

The figure is a perspective view of a piano case, showing our design.

The characteristic features of our design reside in the portion shown by means of full lines in the drawing.

We claim:

The ornamental design for a piano case, as shown and described.

WILLIAM MILLINGTON.
WILBUR M. DAY.
